DESIGN FOR A PRESSURE COOKER

James Harvey Chandler, Oak Park, and Myron J. Zimmer, Wooddale, Ill., assignors to The Edward Katzinger Company, Chicago, Ill., a corporation of Illinois

Application April 5, 1944, Serial No. 113,146

Term of patent 14 years

(Cl. D44—8)

To all whom it may concern:

Be it known that we, James Harvey Chandler and Myron J. Zimmer, citizens of the United States, residing at Oak Park, in the county of Cook and State of Illinois, and Wooddale, in the county of Du Page and State of Illinois, respectively, have invented a new, original, and ornamental Design for a Pressure Cooker, of which the following is a specification, reference being had to the accompanying drawing, forming part thereof.

Fig. 1 is a top plan view of a pressure cooker, showing our new design.

Fig. 2 is a side elevational view of the same.

The dominant feature of this design resides in the portion shown in full lines.

We claim:

The ornamental design for a pressure cooker, as shown and described.
